UNITED STATES PATENT OFFICE

168,288

SELF-SERVICE DISPLAY CONTAINER

Donald A. Cameron, Cranston, R. I.

Application May 7, 1952, Serial No. 19,632

Term of patent 14 years

(Cl. D80—11)

To all whom it may concern:

Be it known that I, Donald A. Cameron, a citizen of the United States, residing at Cranston, county of Providence, State of Rhode Island, have invented a new, original, and ornamental Design for a Self-Service Display Container, of which the following is a specification, reference being had to the accompanying drawing, forming a part hereof.

In the drawings,

Fig. 1 is a perspective view of a self-service display container, showing my novel design;

Fig. 2 is a front view of a self-service display container; and

Fig. 3 is a side view thereof.

I claim:

The ornamental design for a self-service display container, as shown.

DONALD A. CAMERON.
